PRODUCER GAS PROCESS

Filed Aug. 31, 1921

UNITED STATES PATENT OFFICE

HEINRICH KOPPERS, OF ESSEN-RUHR, GERMANY, ASSIGNOR TO THE KOPPERS DEVELOPMENT CORPORATION, OF PITTSBURGH, PENNSYLVANIA, A CORPORATION OF PENNSYLVANIA

PRODUCER-GAS PROCESS

Application filed August 31, 1921, Serial No. 497,372, and in Germany March 14, 1918.

(GRANTED UNDER THE PROVISIONS OF THE ACT OF MARCH 3, 1921, 41 STAT. L., 1313)

This invention relates to a process for avoiding excessive wear of the iron shaft jackets of gas producers or generators operated with low pressure steam.

5 For the well known rotary grate gas generators with iron and therefore cooled shafts, it has been understood in the past that in the double-walled shaft mantle or jacket the cooling water must not be permitted to heat 10 above 70° centigrade, so as to preclude the formation of steam under all circumstances. Temperatures of up to 80° centigrade have been pronounced admissible only when special measures are provided for supervision 15 and immediate action in case of excesses. Such is the practice in the operating regulation of the Kerpely producers or generators. Such generators are exemplified by United States Patents 826,036, 1,078,148 and 1,114,072. Instead of the grate being 20 made polygonal it is commonly made circular but mounted eccentrically.

Now, in connection with gas generators or producers thus operated in accordance with 25 such instructions, a peculiar phenomenon appears inasmuch as the cooling jacket on the inside of the ash-zone wears out with undue quickness.

The invention is built up on the realization 30 that from the mixture of air and steam and from the vapors which result in the water pan through hot ashes, water is precipitated on the inner surface of the metallic wall of gas producers or generators which, 35 in conjunction with the hydrogen sulphide released from the ashes, and the oxygen of the air, causes a violent rusting of the inner part of the stationary shaft section below the fire zone, this corrosion being helped 40 along still further by the high temperature prevailing there. It must be borne in mind here that in such gas generators it is necessary to introduce large quantities of steam in addition to the low pressure air. By the 45 layer of ashes and slag moving against the shaft wall on the revolving grate gasifiers, the rust which forms is always ground off and new inner surfaces thus exposed to the attacks.

50 According to late theories, the rusting is

to be attributed to electrolytic effects, in which connection the water represents the electrolyte and the hydrogen sulfide also plays a certain part. Now, inasmuch as the water reaches the gas producer only in the 55 form of steam from the very first, so that it can only exercise its effect after condensation on the shaft walls, the invention aims at avoiding this water condensation opposite the ash zone on the inner surface of the 60 cooling jacket forming the shaft walls by means of superheating of the contents of the cooling jacket, within the limits between which it can be accomplished at all in view of the partly contradictory requirements. 65 Inasmuch as the surplus heat must be discharged from the fire zone situated above the ash zone and it is impossible, in actual practice, to obtain an accurate division between the two zones which, for that matter, 70 also shift around constantly, this superheating of the steam coming into contact with the shaft wall must be connected with a cooling, by which a contradiction seems to be created.

The new process is characterized by the fact that instead of the hitherto adopted cooling with cold or re-cooled water, cooling is effected with highly preheated water, that is to say, water preheated up to close to the 80 boiling limit, by which means the conditions contradicting each other in the first place are complied with, inasmuch as, on the one hand, the surplus heat from the fire zone proper of the gas producer is discharged 85 with certainty, while a local undercooling along the inner surface of the jacket is avoided in the ash-zone which might give rise to the condensation of the steam. Let it be recalled here that the condensing point 90 of steam is not situated at 100° C. here but, due to the simultaneous presence of air, is below the boiling limit. Generally speaking, the dew point of the entering air and steam mixture is located around 60° C., that is, 95 just around the proximity of the present maximum temperature of the cooling water.

Now, in order to avoid, in connection with such cooling by highly preheated water, the formation of steam, hitherto feared even at 100

much lower temperatures, the water is at the same time introduced under such pressure that the boiling temperature moves correspondingly upward. This will result in a formation of steam from the water taking place only when the latter is again relieved of the pressure prevailing in the cooling jacket. In all other respects, too, of course all conditions are now adapted to the operation with highly preheated water. Instead of water under pressure, a special cooling liquid of a higher boiling point can also be used. At any rate, in connection with such feeding of cooling jackets of gas producers with highly preheated water under suitable pressure or a higher boiling liquid, the desired superheating of the steam coming into contact with the gas producer in the ash zone is attained without the cooling effect of the fire zone proper being affected thereby.

In order to make the invention more clearly understood the same is illustrated in the accompanying drawing, but not limited to the details shown, which may be varied without departing from the invention.

In said drawing the figure is an elevation of a gas producer embodying the invention. Referring to the drawing, 1 is the shaft 30 of the gas producer provided near the grate with a cooling jacket a portion of which cooling jacket is indicated at 2 by dotted lines. 19 indicates, in outline, an ordinary rotary step-grate which is fixed to the ash- 35 pan 20. Heated water is supplied within this jacket 2 by a pipe 3 descending from a water reservoir 4 which is suitably supported at a point higher than the cooling jacket. The pipe 3 leads from near the bottom 40 of the reservoir to near the bottom of the jacket, substantially as shown, entering the latter at 5. In the process of cooling the jacket the water is further heated and rises, and enters at 6 a return pipe 7 which 45 enters the reservoir near the top of the body of water therein. Thus a thermosiphon circulation of the cooling (but preheated) body of water is maintained, from the reservoir to the cooling jacket and from the latter to 50 the reservoir. A certain amount of steam is produced from the circulating body of water and such steam finds a passage from the jacket to the upper part of the reservoir by means of a steam pressure relief vent or 55 pipe 8, and is utilized for (or for a part of) the usual steam supply to the fuel within the producer. This is accomplished by a steam pipe 9 which leaves the upper part of the reservoir at 10 and delivers below the 60 grate 19 at 11 adjacent the customary air supply conduit 21. The steam pipe 8 prevents any steam pressure from obstructing the hot water circulation. Water is supplied to the reservoir by a pipe 12, and this is or 65 may be preheated in a heater 13 by excess

and waste steam which leaves the reservoir by the pipe 14. The described pipes are controlled suitably by valves, as indicated, for the water supply pipe at 15, for the downward and upward water-circulation pipes at 16 and 17, and for the steam supply pipe at 18.

In its main features the gas producer is or may be of usual or preferred construction, not requiring to be further described.

In operation, the producer when coke fired is preferably operated in the following well-known manner. Air from conduit 21 and steam from pipe 9 are supplied continuously to the usual fuel bed (coke or other fuel)

below the grate 19 and passed upwardly therethrough. The combustion of the coke generates considerable heat, creating an incandescent fire zone in the fuel bed. The carbon dioxide produced by the combustion

and water vapor admitted with the air blast react with the incandescent fuel, giving the combustible gases, carbon monoxide and hydrogen, diluted with the inert nitrogen of the air. On top of the grate 19 is main-

tained an ash zone 22 comprising a layer of ash about a foot high above the apex of the grate 19. This ash zone is usually at a sufficiently high temperature to prevent condensation of steam and in fact gives up

heat to the air and steam thereby heating the air and superheating the steam and simultaneously cooling the ash for discharge.

Above the ash zone is maintained the fire zone 23 varying in thickness with grade and kind of fuel used, as, for instance, from two

inches with coke breeze to about a foot with stove coke. Above the fire zone is the coke or distilling zone 24 wherein the fuel reaches a height of from three to six feet above the fire zone. When the air blast encounters

the fire zone the oxygen combines with the carbon to carbon dioxide. The oxygen in the air is quickly used up and the carbon

dioxide encountering the incandescent fuel is reduced to carbon monoxide. The combustion to carbon monoxide generates a

great amount of heat, which is partly consumed in reducing carbon dioxide to carbon monoxide. The remaining heat is dissipated

by radiation and absorption by the cooling water in the water jacket and some of the remaining heat passes out of the producer

with the combustible gas. Were not the steam passed into the fuel bed with the air during manufacture of producer gas, the temperature in the fire zone would become

too hot for commercially successful operation. The ash of the fuel fuses and forms

clinkers at temperatures quite close to the operating temperature of the producer. By admitting steam along with the air blast, control of the temperature resulting from

the air blast is readily effected. When water vapor encounters incandescent fuel it is re-

duced to hydrogen and carbon monoxide, the oxygen being taken up by the carbon forming carbon monoxide. This reaction absorbs heat, so that by controlling the amount of steam admitted by the pipe 8, the temperature of the fire can be regulated. At temperatures below 1160° C. the reaction between carbon and carbon monoxide and water vapor becomes but partial and is retarded, so that the fire zone is usually maintained above said temperature and the ash zone below said temperature but high enough to superheat the steam. The proper temperature varies according to the composition of the ash. A reliable method of controlling the amount of steam admitted is by saturating the air blast to a certain temperature which for average conditions is about 54° C. This temperature will vary with the rate at which the coke is gasified as well as with its composition. The gas leaves the producer through the outlet 25 as shown at the upper part of the producer from which it is passed to other apparatus to be further treated for removal of dust, etc., or it may be passed from said outlet directly to the place where it is to be employed for combustion.

The water jacket 2 extends far enough, as indicated on the drawings, so that the fire zone will never pass beyond it, and thus prevents side clinkers which would form on the brick lining of the producer. The steam drum is so connected as to induce a thermosiphon circulation through the water jacket 2 and the steam reservoir 4. With the water and steam reservoir 4 located above the top of the water jacket 2 as shown, the water enters the jacket at about 100° C., and the jacket is operated under a pressure of about five pounds per square inch, which prevents any boiling action in the jacket. This corresponds to a temperature of 108° C. which prevents any condensation of steam from the blast on the wall of the jacket below the fire zone and opposite the ash zone, which would rust the jacket and result in rapid wear, and thereby reduce the generating capacity of the producer by reason of the condensation of the gas making steam and the more numerous shut downs of the producer for purposes of relining the walls thereof. As the water becomes heated it flows upwardly into the reservoir 4 below and near the water level therein where it is relieved of such pressure and flashes into steam. The residual water thence flows back as it cools toward the inlet to the jacket 2. The steam that forms in the steam space above the top level of the water space in the reservoir is conducted by pipe 9, as above described, to the lower portion of the producer, where it mixes with the air from conduit 21, and is then passed into the fuel bed to thereby form producer or other com-

bustible gas. Of course, the steam from the pipe 9 of the reservoir also may be used for other purposes than for supplying the producer, and steam or the equivalent thereof from other sources may be employed as an equivalent of the steam from the reservoir 4, thereby releasing all steam from reservoir 4 for other uses.

What is claimed is—

1. A process of making producer gas in a gas producer having a metallic water jacket and a water and steam reservoir located entirely thereabove and having a lower water space and an upper steam space, and also having a gas producing chamber having a fuel gasifying zone and an ash zone, which comprises: circulating water from the lower portion of the water space of the reservoir downwardly into the bottom of the water jacket and passing thereto at a temperature of about 100° C. and then upwardly through the top into the water reservoir near and below the top level of the water therein by thermosiphon circulation of the water induced by the surplus gas making heat absorbed thereby but under sufficient pressure so that steam formation takes place substantially only in the reservoir; passing steam from the steam space of the reservoir to the lower portion of the gas producer, mixing with air, passing the mixed steam and air into and through the ash zone of the gas producing chamber and then into the fuel gasifying zone and thereby forming producer gas; the ash zone and the fuel gasifying zone being enclosed by the water jacket and the ash zone having a sufficiently high temperature to prevent condensation of steam upon the inside surface of the water jacket. 100

2. A method of making gas from a fuel bed in a gas producer having a gas producing chamber having a fuel gasifying zone and an ash zone, and also having a metallic water jacket enclosing the fuel gasifying zone and the ash zone, and a water and steam reservoir located entirely above the water jacket and having a lower water space and an upper steam space, which method comprises: passing steam and air into and through the ash zone of the fuel bed in the gas producing chamber to absorb heat from and thereby cool the ash, and then into and through the fuel gasifying zone thereby forming combustible gas with said air and said steam; water-cooling the walls of said fuel gasifying zone and said ash zone down to a temperature sufficiently high to prevent condensation of the gas making steam upon the inside surface of the water jacket adjacent the ash zone and to discharge surplus heat from outer portions of the fuel gasifying zone adjacent said jacket; effecting such water cooling by thermosiphon circulation of water, induced by surplus gas making heat absorbed thereby, from the lower portion of 130

the water space of said reservoir downwardly into the bottom of the water jacket and passing thereinto at a temperature of about 100° C., and then upwardly through the top thereof and into the water reservoir near and below the top level of the water therein, and under the pressure of the water in the water space of said reservoir so that the boiling point of water in said jacket is above 100° C.

5 and that substantial steam formation takes place only in the reservoir and is removed from the circulating water into said steam space.

3. A method as claimed in claim 2 and
15 in which cool feed water admitted to the circulating system is supplied to the system in advance of the inflow into the water jacket and is regulated so that such feed water may mix with and be heated by the hot inflow stream of water and be prevented from locally chilling the water jacket circulation.

4. A method as claimed in claim 2 and which includes the further step of venting
25 steam, that may form in the stream of water flowing upwardly from the water jacket into the water space, from the circulating body of water.
